(57) **CLAIM**

The ornamental design for a big fish arrowhead adaptor, as shown and described.

DESCRIPTION

FIG. 1 is a left side elevational view showing my new design for a big fish arrowhead adaptor which is a mirror image of the right side;

FIG. 2 is a left side elevational view partially broken away to show proximal threads;

FIG. 3 is an assembled left side elevational view which is a mirror image of the assembled right side;

FIG. 4 is a top plan view of the assembled right side which is a mirror image of the bottom plan view;

FIG. 5 is a left side elevational view with the barbs rotated for arrowhead removal from a fish;

FIG. 6 is a front elevational view; and,

FIG. 7 is a rear elevational view.

The broken line drawings of the fishing arrowhead are for illustrative purposes only and form no part of the claimed design.
